MEANS FOR CONTROLLING THE PRODUCTION OF WATER VAPOR BY AND SUPPLY TO GAS PRODUCERS

Albert Leet Galusha, Caldwell, N. J.

Application October 31, 1936, Serial No. 108,654

8 Claims. (Cl. 48—76)

This invention relates to gas producers and more particularly to means for controlling the production and supply of steam or water vapor to gas producers and it is an object of this invention to provide an improved means of the class described which will permit of the gas producer supplying all steam or water vapor necessary for its operation; which will automatically maintain the supply of steam or water vapor in accordance with the rate of gas production and which will maintain the mixture of air and steam or water vapor supplied the gas producer at a substantially uniform temperature. It is also an object of this invention to provide means for preventing the accumulation of ash at or on the gas producer wall and the reduction in the volume of steam or vapor generated by the producer as the result thereof because of the reduction in the amount of heat transmitted through the gas producer wall to the water in the water jacket.

In the drawing—

Fig. 1 is a partial view in vertical section of a gas producer constructed in accordance with this invention, supply pipes connected to the gas producer being shown partly in elevation and partly diagrammatically; and

Fig. 2 is a partial horizontal sectional view showing the grate of Fig. 1 in plan view, parts being broken away to show other parts more clearly.

As shown in the drawing a gas producer constructed in accordance with this invention is provided with an annular wall comprising an inner wall 1 and an outer wall 2 spaced from the inner wall and forming an annular space which is sealed at the bottom by a plate 3 to form a water jacket. The inner and outer wall members 1 and 2 are connected to inner and outer top members 4 and 6, respectively, which are also spaced apart to form a water jacket for the top of the gas producer. The top members 4 and 6 are spaced apart a greater distance than are the walls 1 and 2 and are provided with aligned openings in which are fitted the fuel feeding tubes 8 and the frame of the manhole or inspection opening 10. The outer top member 6 is also provided with an opening to which is connected the pipe 12 leading from the blower or air blast connection 14 and an opening to which is connected a pipe 18. The pipe 18 is connected through a pipe 20 to the inlet pipe 22 by which air is supplied to the gas producer casing, passing through grate 24 to the fire.

Water for the water jacket of the gas pro-

ducer is supplied from a supply line 26 through branch pipes 28, 30 and 32 and pipe 34 to the water jacket at the top of the gas producer. Excess water is discharged from the water jacket through an overflow pipe 36 which has a portion thereof bent to U-shape, as at 36', to form a water seal which prevents the escape of air or steam from the water jacket. The overflow pipe 36 is positioned to maintain a proper depth of water on the inner top member 4 and the spacing of the top members 4 and 6 is such that there is sufficient space for the passage of air from the pipe 12 over the water in the water jacket to the pipe 18 in its passage from the blower 14 to the gas producer. When the gas producer is in operation the air in passing over the water in the water jacket is heated and absorbs moisture as its temperature is raised.

In order to maintain the condition of the air supplied to the gas producer uniform as to the moisture content thereof it is necessary to maintain the air at a uniform temperature. To accomplish this there is provided a bulb 38 filled with a gas or liquid which is expanded or partly vaporized at the temperature at which it is desired to maintain the air supplied to the gas producer. The bulb 38 is connected by a capillary tube 40 to an expansible diaphragm 42 which is connected through the stem 44 to the balanced throttle valve 46 in the branch pipe 28. The diaphragm 42 is arranged to be operated upon increase in temperature in the air pipe 20 to open the throttle valve 46 further against the action of the spring 48 to increase the flow of water to the water jacket of the gas producer, cooling the water in the water jacket and reducing the temperature to which the air passing thereover is heated and the amount of moisture taken up by the air in its passage through the water jacket. If the temperature of the air falls below the desired temperature the gas or liquid in the bulb 38 is cooled and the pressure on the diaphragm 42 is reduced permitting the spring 48 to operate the throttle valve 46 and reduce the flow of water to the water jacket. With the flow of water to the water jacket reduced the temperature of the water in the water jacket is raised causing the temperature of the air and the amount of moisture taken up by the air to be increased. As the volume of water in the water jacket is considerable the variations in its temperature are gradual and the necessary movements of the throttle valve 46 slow.

In the drawing the branch pipe 28 is shown provided with a strainer 50 to prevent dirt reach-

ing the throttle valve 46, and to permit of continuous operation while the strainer 50 is being cleaned the branch pipe 30 is provided. A valve 52 in the branch pipe prevents flow therethrough when the branch pipe is not in use and serves to regulate the flow when the branch pipe is in use. A valve 54 in the branch pipe 28 and a valve 56 in the pipe 34 serve to cut out the branch pipe 28 while the strainer is being cleaned. Normally the valves 54 and 56 are open and the valve 52 is closed. A branch pipe 32 of larger size and having a valve therein is provided in order to accomplish the initial filling of the water jacket more rapidly. The branch pipe 32 is kept closed during the operation of the producer.

In service, particularly when the gas producer is being called upon to produce a large volume of gas continuously for a considerable period, combustion of the fuel tends to take place more rapidly adjacent the gas producer wall with a resulting accumulation of ash which, after a period of operation, tends to reduce the amount of heat transferred to the water in the water jacket and cause a reduction in the temperature of the cooling water and a reduction in the amount of steam produced. In order to maintain a substantially constant condition of the fire with respect to the accumulation of ash at the gas producer wall the grate 24, which consists of annular plates 24^a, 24^b and 24^c and a cap piece 24^d, eccentrically mounted in spaced relation on a frame 24^e pivotally mounted on a suitable support 25, is provided with a scraper mounted on the grate plate 24^b for preventing accumulation of ash or clinker adjacent the gas producer inner wall 1. The scraper comprises a bar or member 27 secured by bolts 29 on the grate plate 24^b, between projections 24^f welded to the plate, and projecting outwardly into the region of the producer wall 1. At its outer end the member 27 is formed with a vertically extending portion 27^a positioned at an acute angle to the wall 1 and cut away at its front portion to provide a cutting edge of chisel-shape having the toe closer to the producer wall than the heel. The bolts 29 securing the scraper bar 27 to the plate 24^b are placed with the nuts 29^a beneath the plates to permit of the removal or replacement of worn or damaged scrapers without dumping the fire, it being found that the ash will "arch over" sufficiently to permit of the work being done.

The rotation of the scraper 27, 27^a tends to rotate the fuel bed with the grate 24 and to prevent this rotation vertical ribs or projections 31, 55 projecting radially inwardly of the gas producer and having their upper end portions tapering to prevent fuel or ash lodging thereon, are welded or otherwise suitably secured to the inner face of the wall 1 at uniformly spaced points and at 60 height slightly above the upper level of the vertical portion 27^a of the scraper so that the projections 31 cooperate with the scraper in breaking large pieces of clinker or ash.

The angular position of the vertical portion 27^a of the wall scraper tends to force the ash inwardly to be discharged over the inner edges of the grate plates and this operation is assisted by the ash scrapers 33 secured at openings in the gas producer wall and projecting inwardly over the 70 lowermost grate plate 24^a. The inner end portions of the scrapers 33 are bent slightly in the direction of rotation of the grate and cooperate with the wall scrapers 27, 27^a in forcing the ash inwardly over the inner edges of the grate plates. 75 The scrapers 33 have their upper edge portions

spaced slightly below the bottom of the wall scraper 27, 27^a so as to pass without interference while cooperating therewith in the breaking of large pieces of clinker or ash.

Where it is desired to supply steam from an outside source, as through pipe 60 and cone 62, the supply of steam can be regulated by a valve similar to valve 46 but arranged to be opened when the temperature in pipe 20 falls and vice versa. In this case water is supplied through a branch pipe having a manually controlled valve therein as the branch pipe 30 and valve 52, the valve being kept open to such an extent that an excess of water is supplied and the air is not heated to the desired temperature in passing through the water jacket, the steam supplied through pipe 60 bringing the air to the desired temperature and moisture. As a check on the condition of the air supplied to the gas producer, a thermometer 64 of either the indicating or recording type, is provided, the air having the desired moisture so long as it is maintained at the correct temperature.

Inasmuch as the moisture content of saturated air varies with changes in the air temperature, 25 saturated air at 140° F. containing about four times the moisture of saturated air at 100° F., the proper amount of moisture can be supplied to the fire by maintaining the air supplied at the proper temperature. With all the air supplied of uniform moisture content there is but little variation in the quality of the gas produced regardless of the demands made upon the producer and with the fire maintained in substantially uniform condition for transferring heat to the water jacket, 35 the control of the air temperature and thus of the volume of moisture supplied to the fire is effected by the control of water supplied to the water jacket by the response of the fluid in the bulb 38 to changes in the air temperature. In 40 this way the temperature of the water jacket is controlled so as to supply the desired amount of moisture to the air supplied to the fire and the supply of excess moisture to the fire and the cooling of the fire resulting therefrom prevented. 45

What is claimed is:

1. The combination with a gas producer having a water jacket, of means for heating and moistening in said water jacket all air supplied to the gas producer fire, means for supplying water to said water jacket, means for removing ash from a wall of said water jacket to maintain substantially uniform conditions for the transfer of heat from the fire to said water jacket and means responsive to variations in the temperature of the air supplied for controlling said water supplying means.

2. In a gas producer having relatively rotating wall and grate, a scraper carried by said grate for removing ash from said wall, ribs on said wall above the path of said scraper preventing rotation of the fuel bed with the scraper and ash plows projecting inwardly beneath the path of said scraper for forcing the ash inwardly over the grate.

3. In a gas producer having a rotating grate and a fixed wall, a scraper rotating with said grate for removing ash from said wall, ribs extending vertically on said wall above the path of said scraper preventing rotation of the fuel bed with said scraper and ash plows fixed relatively to said ribs and projecting inwardly beneath the path of said scraper for forcing ash inwardly over the grate.

4. In a gas producer having relatively rotat-

ing wall and grate, a scraper for the wall carried by the grate, vertically extending ribs on said wall above the zone of the scraper and ash plows projecting inwardly beneath the zone of the scraper, said scraper cooperating with said ribs and ash plows in crushing waste pieces of clinker.

5. The combination with a gas producer having a water-jacket, of means for supplying all air for the gas producer fire through said water-jacket and means responsive to variations in the temperature of the air supplied to the producer fire for maintaining constant the temperature and moisture content of the air supplied.

10 6. The combination with a gas producer having a water-jacket, of means for supplying all air for the gas producer fire through said water-jacket and means responsive to variations in the temperature of the air supplied to the producer fire for controlling the temperature of the water in the water-jacket to maintain constant the

temperature and moisture content of the air supplied to the producer fire.

7. The combination with a gas producer having a water-jacket of means for supplying all air for the gas producer fire through said water-jacket and means responsive to variations in the temperature of the air supplied for controlling the supply of water to the water-jacket to maintain constant the temperature and moisture content of the air supplied to the producer fire.

15 8. The combination with a gas producer having a water-jacket, of means for passing all air for the gas producer fire over water in said water jacket, means for supplying water to said water-jacket and means responsive to variations in the temperature of the air supplied to the gas producer fire for controlling the supply of water to the water-jacket to maintain constant the temperature and moisture content of the air supplied.
